REFRIGERATING APPARATUS

Frank W. Gerard, Dayton, Ohio, assignor to General Motors Corporation, Dayton, Ohio, a corporation of Delaware

Application November 20, 1940, Serial No. 366,442

8 Claims. (Cl. 62—8)

This invention relates to refrigerating apparatus and particularly to means for controlling the flow of liquid refrigerant from the refrigerant compressing and liquefying unit to the evaporator.

In many refrigeration applications restrictors have replaced valves for controlling the flow of liquid refrigerant from the condenser to the evaporator. The chief reason for this is because of the simplicity of a restrictor which renders the same substantially foolproof to thus reduce service troubles. Restrictors, however, do not accommodate varying refrigeration loads as well as desired. In restrictor type systems use is made of a varying condensing pressure and the cycling of the system to secure some variation of the liquid flow in accordance with varying loads. However, it has been found that in ordinary systems the restrictor will not produce sufficient throttling of the flow of liquid refrigerant to the evaporator under high temperatures and high refrigerant condensing pressure conditions. An abnormally high condensing pressure causes too much liquid refrigerant to be forced through a capillary passage of a restrictor and as a result thereof the evaporator becomes full of liquid refrigerant which slopes or flows therefrom into the suction line and causes this line to become frosted. Operation of a refrigerating system under this condition is rather inefficient and highly undesirable.

It is an object of my invention to reduce the flow of liquid refrigerant through a capillary passage of a restrictor under high temperature and high pressure conditions to prevent an accumulation of an excessive amount of liquid refrigerant in the evaporator.

Another object of my invention is to provide means for changing the cross-sectional area of a capillary passage of a restrictor of a refrigerating system which means is rendered effective automatically in response to temperatures exteriorly of the food storage compartment to be cooled by the evaporator of the system.

A further object of my invention is to provide a restrictor for a refrigerating system with a continuously open capillary refrigerant restricting passage of great length in proportion to its cross-sectional area that is of a predetermined restriction to the flow of liquid refrigerant to the evaporator under normal temperature and pressure conditions and which restriction thereof is increased under high temperature conditions for

reducing the flow of liquid refrigerant therethrough in its passage to the evaporator.

In carrying out the foregoing objects it is a still further and more specific object of my invention to provide a restrictor of a refrigerating system with an insert member that has a greater coefficient of expansion and contraction than walls of the restrictor in which it is confined and which insert is provided with a continuously open capillary refrigerant restricting passage, the cross-sectional area of which is reduced automatically by its expansion within the confinement of walls of the restrictor due to an increase in temperature outside the compartment being cooled by the system.

Further objects and advantages of the present invention will be apparent from the following description, reference being had to the accompanying drawing, wherein a preferred form of the present invention is clearly shown.

In the drawing:

Fig. 1 is a vertical sectional view of a refrigerating apparatus having a refrigerating system associated therewith;

Fig. 2 is an enlarged sectional view of the restrictor of the refrigerating system shown in Fig. 1 and constructed in accordance with my invention;

Fig. 3 is a sectional view of the restrictor taken on the line 3—3 of Fig. 2 showing the normal diameter of the refrigerant restricting capillary passage; and

Fig. 4 is a view similar to Fig. 3 showing the diameter of the refrigerant restricting capillary passage diminished.

In Fig. 1 of the drawing I have shown a refrigerating apparatus of the household type comprising a cabinet 10 having insulated walls 11 forming a food storage compartment 12 therein and including a closed refrigerant circulating system or circuit associated with the cabinet. The closed refrigerating system includes a refrigerant compressing and liquefying unit comprising a sealed motor-compressor 14 for compressing refrigerant and for forwarding the compressed refrigerant to a condenser 15 where the compressed refrigerant is liquefied and collects therein. From the condenser 15 the liquid refrigerant is forwarded through a supply conduit 16 to a restrictor element 17 and through a small, preferably insulated, conduit 18 to an evaporator 19. The evaporator 19 is mounted in the upper portion of the food compartment 12 which is to be cooled

and the restrictor element 17 controls the flow of liquid refrigerant thereinto. Liquid refrigerant vaporizes within the evaporator 19 under reduced pressure and the evaporated refrigerant returns to the compressor through a suction conduit 21. In order to provide for intermittent operation of the motor-compressor 14 a thermostatic switch (not shown), actuated in response to the refrigerating effect produced by evaporator 19, may be connected into the electric circuit leading to the motor-compressor 14. The method of actuating such a switch by a thermostat bulb and the construction of the switch itself is now conventional and forms no part of the subject matter of the present application. The restrictor element, generally represented by the reference character 17, of the refrigerating system is, in the present illustration, mounted exteriorly of the insulated walls 11 of compartment 12 and preferably within the outer sheet metal walls of cabinet 10. The restrictor of the present invention is variable in response to its environment temperature in a manner and for a purpose to be herein-after more fully described. For example, the restrictor element 17 in the present disclosure is exposed to temperatures outside the compartment 12 and of the room within which the refrigerating apparatus is located. Motor-compressor 14 and condenser 15 of the refrigerant compressing and liquefying unit of the refrigerating system may be mounted in a machine compartment of cabinet 10 located below the food compartment 12.

The restrictor element 17 better shown in Fig. 2 includes a metal housing 25 having a large round bore 26 therein threaded at one end as at 27 and provided at its other end with a threaded boss or projection 28. A small bore 29 extends from the inner wall of bore 26 through the threaded boss 28. The pipe or conduit 18, which leads from the restrictor to the evaporator of the refrigerant circuit, is secured to element 17 by a nut 31 threaded upon the boss 28. I place a non-metallic round elongated plug-like member or means 33, having an opening 34 provided centrally thereof, within the bore 26 of housing 25 and locate a metal washer 36, having a hole 37 centrally thereof, at one end of member 33. An adjustable metal clamping gland 39, having a hole 41 centrally thereof, is threaded as at 42 upon the threads 27 of housing 25 and abuts the washer 36. Gland 39 is provided with a key or screwdriver slot 44 to permit adjustment thereof within the bore 26 and against washer 36. A nut 45 threaded into the threads 27 of housing 25 has a gasket 46 disposed under a shoulder formed thereon and clamped against the end portion of housing 25 to seal the same against leakage of refrigerant at this point. Nut 45 is also provided with a threaded projection or boss 47 which receives a nut 48 for securing the liquid refrigerant supply pipe or conduit 16 to the element 17. An opening 49 extends through nut 45 and its boss 47 to permit flow of refrigerant from pipe 16 into the element 17.

The opening 34 located centrally within member 33 forms a continuously open substantially capillary passage within element 17 preferably, although not necessarily, of great length in proportion to its cross-sectional area so as to serve as the sole means for controlling the flow of liquid refrigerant from the condenser 15 to evaporator 19. The member 33 is preferably formed of a resilient rubber-like material, such as a compound which includes a polymer of chloroprene

or neoprene, of the type sold under the trade name of "Duprene." The material of member 33 as constructed is resistant to the refrigerant and oil used in the refrigerating system and has the characteristic of being expansible and contractible in response to changes in temperature thereof. The member 33 has a greater coefficient of expansion and contraction than the metal walls of housing 25 of restrictor element 17 and since, as before stated, the element 17 is mounted outside the compartment 12, member 33 therein is subject to its environment temperatures.

After placing plug-like member 33 within the bore 26 of housing 25 the member 33 is confined by the one flat end wall and round side wall of the bore and at its other end by the washer 36. This confinement of member 33 within element 17 permits the adjustable gland 39 to be tightened against washer 36 to firmly clamp member 33 within the restrictor housing 25. The elongated hole 34 in member 33 is set, by the clamping gland 39, to a predetermined diameter or cross-sectional area to offer the proper or a predetermined resistance to the flow of liquid refrigerant through the restrictor element 17 in its passage to the evaporator under normal operating temperature conditions. The confinement of member 33 by walls of housing 25 and the predetermined clamping thereof within the bore 26 maintains the proper cross-sectional area of the hole 34 for normal operating temperatures as balanced against the normal temperature of refrigerant flowing through the restrictor. However, this confinement of member 33 also causes the diameter or cross-sectional area of the restricted refrigerant passage 34 to be reduced when the temperature of member 33 is increased above normal room temperature or increased when the temperature of the room is decreased. Since a rise in temperature of member 33 creates expansion thereof its method of confinement causes the same to expand in a direction toward the passage 34 to thereby reduce the diameter thereof substantially uniformly along its length. Conversely, a drop in the temperature of member 33 creates contraction thereof to cause enlargement of the cross-sectional area of the capillary passage 34. This characteristic of member 33 is utilized for varying the amount of liquid refrigerant flowing through the restrictor element to the evaporator in response to environment temperatures about element 17.

The refrigerant restricting passage 34 of element 17 may normally offer the proper resistance to the flow of refrigerant to the evaporator of the refrigerating system within the ordinary temperature ranges maintained in the room in which the refrigerating apparatus is located in accordance with normal pressures in the system which affect the flow of refrigerant therethrough. However, an abnormal rise in temperature within the room, such as a period of several days of very hot weather during the summer, will cause the temperature and consequently the pressure of refrigerant in the condenser to increase. Without some means for varying the size of the capillary passage of the restrictor this increased pressure of refrigerant within the condenser will force too much liquid refrigerant through the passage and into the evaporator. My invention eliminates the difficulties hereinbefore pointed out in that when this abnormal high temperature occurs the refrigerant restricting passage of the restrictor element automatically offers more restriction to the refrigerant flow to thereby pre-

vent too great a flow of liquid refrigerant into the evaporator. The abnormal high temperature is transmitted through the metal walls of the element 17 to member 33 therein and this higher temperature will cause expansion of member 33. Due to the confinement of member 33 within the element 17 as herein disclosed, the expansion thereof is in a direction to diminish the diameter or cross-sectional area of passage 34 and its smaller diameter, see Fig. 4, as compared to its normal diameter, see Fig. 3, affords greater resistance to the flow of refrigerant from the condenser to the evaporator to thereby prevent the higher pressure in the system from circulating too much refrigerant through the restrictor. In other words, as the temperature exteriorly of the refrigerated food compartment increases abnormally this temperature affects the restrictor member simultaneously with the attending increase in pressure of refrigerant in the condenser and causes a reduction in the size or cross-sectional area of the capillary passage of the restrictor. The additional restricted flow of liquid refrigerant to the evaporator counterbalances the increase of refrigerant pressure within the system to thereby provide efficient operation of the system without the difficulties heretofore enumerated.

Irrespective of the location of the restrictor element, a drop in the temperature surrounding same causes the capillary passage forming element thereof to contract. Contraction of this member enlarges the cross-sectional area of the refrigerant restricting passage and permits sufficient liquid refrigerant to flow into the evaporator to provide efficient refrigeration within the food storage compartment of the refrigerator cabinet under low temperature conditions, which conditions might otherwise diminish the flow of refrigerant to the evaporator to such an extent that the evaporator would be starved of liquid refrigerant. Thus, in the present disclosure the member within the restrictor element forms the liquid refrigerant restricting means as well as forming its own adjustment thereof in response to the environment temperature of the element.

While the form of embodiment of the invention as herein disclosed, constitutes a preferred form, it is to be understood that other forms might be adopted, all coming within the scope of the claims which follow.

What is claimed is as follows:

1. A refrigerating apparatus comprising, a cabinet having a compartment therein to be cooled, a closed refrigerant circuit associated with said cabinet, said circuit including an evaporator for cooling said compartment, a refrigerant compressing and liquefying unit and a restrictor element exposed to temperatures exteriorly of said compartment, means within said restrictor element and forming a continuously open capillary passage therethrough of great length in proportion to its cross-sectional area for controlling the flow of liquid refrigerant from said unit to said evaporator, said passage forming means being expandable and contractible in response to changes in temperature exteriorly of said compartment, and said means being so constructed and arranged that expansion and contraction thereof varies the cross-sectional area of said capillary passage.

2. A refrigerating apparatus, comprising, a cabinet having a compartment therein to be cooled, a closed refrigerant circuit associated with said cabinet, said circuit including an evaporator for

cooling said compartment, a refrigerant compressing and liquefying unit and a restrictor element exposed to temperatures exteriorly of said compartment, a member confined within walls of said restrictor element and having a greater coefficient of expansion and contraction than the walls thereof, said member having an opening therein forming a continuously open capillary passage therethrough of great length in proportion to its cross-sectional area for controlling the flow of liquid refrigerant from said unit to said evaporator, and said member being expandable and contractible in response to changes in temperature exteriorly of said compartment and being so confined within the walls of said restrictor element that its contraction or expansion varies the cross-sectional area of said capillary passage.

3. A refrigerating apparatus comprising, a cabinet having a compartment therein to be cooled, a closed refrigerant circuit associated with said cabinet, said circuit including an evaporator for cooling said compartment, a refrigerant compressing and liquefying unit and a restrictor element exposed to temperatures exteriorly of said compartment, an elongated plug-like member within said restrictor element and having formed centrally therein a continuously open capillary passage of great length in proportion to its cross-sectional area for controlling the flow of liquid refrigerant from said unit to said evaporator, said member being formed of a material that is expandable and contractible in response to changes in temperature exteriorly of said compartment, and said member being so confined by walls of said element that expansion and contraction thereof is in a direction to vary the cross-sectional area of said capillary passage.

4. A refrigerating apparatus comprising, a cabinet having a compartment therein to be cooled, a closed refrigerant circuit associated with said cabinet, said circuit including an evaporator for cooling said compartment, a refrigerant compressing and liquefying unit and a restrictor element exposed to temperatures exteriorly of said compartment, an elongated plug-like member within said restrictor element and having formed centrally therein a continuously open capillary passage of great length in proportion to its cross-sectional area for controlling the flow of liquid refrigerant from said unit to said evaporator, said member being formed of a resilient non-metallic material having a greater coefficient of expansion and contraction than walls of said element, and said member being expandable and contractible in response to changes in temperature exteriorly of said compartment and so confined within the walls of said element that its expansion and contraction is in a direction to vary the cross-sectional area of said capillary passage.

5. A refrigerating apparatus comprising, a cabinet having a compartment therein to be cooled, a closed refrigerant circuit associated with said cabinet, said circuit including an evaporator for cooling said compartment, a refrigerant compressing and liquefying unit and a restrictor element exposed to temperatures exteriorly of said compartment, an elongated member confined within walls of said restrictor element and having a greater coefficient of expansion and contraction than the walls thereof, said elongated member having a continuously open capillary passage centrally thereof of great length in proportion to its cross-sectional area for controlling the flow of liquid refrigerant from said unit to said evaporator, said member being ex-

pansible and contractible in response to changes in temperature exteriorly of said compartment, and said elongated member being so confined within the walls of said restrictor element that its contraction and expansion occurs substantially uniformly along the length thereof in a direction to vary the cross-sectional area of said capillary passage.

6. A refrigerating apparatus comprising, a cabinet having a compartment therein to be cooled, a closed refrigerant circuit associated with said cabinet, said circuit including an evaporator for cooling said compartment, a refrigerant compressing and liquefying unit and a restrictor element, means confined within walls of said restrictor element and having a continuously open substantially capillary passage of great length in proportion to its cross-sectional area extending therethrough for controlling the flow of liquid refrigerant from said unit to said evaporator, said passage forming means having a greater coefficient of expansion and contraction than walls of said restrictor element, and said passage forming means being so confined within the walls of said element that its expansion and contraction therein in response to environment temperature changes varies the cross-sectional area of said capillary passage.

7. A refrigerating apparatus comprising, a cabinet having a compartment therein to be cooled, a closed refrigerant circuit associated with said cabinet, said circuit including an evaporator for cooling said compartment, a refrigerant compressing and liquefying unit and a restrictor element, an elongated plug-like member

confined within walls of said restrictor element and having formed therein a continuously open capillary passage of great length in proportion to its cross-sectional area for controlling the flow of liquid refrigerant from said unit to said evaporator, said passage forming member having a greater coefficient of expansion and contraction than walls of said restrictor element, and said passage forming member being so confined within the walls of said element that its expansion and contraction in response to environment temperature changes varies the cross-sectional area of said capillary passage.

8. A refrigerating apparatus comprising, a cabinet having a compartment therein to be cooled, a closed refrigerant circuit associated with said cabinet, said circuit including an evaporator for cooling said compartment, a refrigerant compressing and liquefying unit and a restrictor element, a non-metallic member confined within walls of said restrictor element and having formed therein a continuously open substantially capillary passage of greater length than its cross-sectional area for controlling the flow of liquid refrigerant from said unit to said evaporator, said passage forming member having a greater coefficient of expansion and contraction than walls of said restrictor element, and said non-metallic passage forming member being so confined by the walls of said element that its expansion and contraction therein in response to environment temperature changes is in a direction to vary the cross-sectional area of said capillary passage.
